UNITED STATES PATENT OFFICE.

CHARLES TOTH PAPAY, OF AMBRIDGE, PENNSYLVANIA.

FOOD CABINET.

Application filed February 6, 1922. Serial No. 534,563.

To all whom it may concern:

Be it known that I, CHARLES TOTH PAPAY, a citizen of Hungary, residing at Ambridge, in the county of Beaver and State of Pennsylvania, have invented new and useful Improvements in Food Cabinets, of which the following is a specification.

My present invention has reference to a food cabinet.

10 My improvement is primarily devised for preserving food in the winter time by arranging the cabinet on the exterior of a building adjacent to a window in a manner whereby the cabinet may be swung through 15 the window opening into a room so that the contents thereof may be removed or articles may be placed therein, and whereby the employment of ice as a refrigerating agent is dispensed with.

20 A further object is to produce a food cabinet that shall be hingedly supported on a frame which in turn is hingedly attached to a suitable support secured to the outside of a building adjacent to a window, the cabinet 25 normally resting against the side of the window, the construction being such as to hold the same in such position regardless of winds or storms and the construction being also such as to permit of the cabinet and 30 frame being swung to arrange the cabinet in the window opening for the removal or the insertion of foodstuffs therein.

The drawings which accompany and 35 which form part of this specification illustrate a satisfactory embodiment of the improvement reduced to practice, and wherein:

Figure 1 is a perspective view looking 40 toward the exterior of the building provided with the improvement.

Figure 2 is a horizontal sectional view taken directly above the cabinet and looking toward the same.

Figure 3 is a substantially similar view 45 but showing the cabinet and frame swung to arrange the cabinet through a window opening in a room.

Figure 4 is a perspective view of the supporting frame for the cabinet.

50 Figure 5 is a perspective view of the cabinet with the door thereof in open position.

If desired, two cabinets, in accordance 55 with this invention may be arranged one to each side of a window on the exterior of a building, but in the drawings I have shown only one of such devices.

Referring now to the drawings in detail, the numeral 1 designates a portion of a building and 2 a window casing in the building which is provided with the usual sliding sashes. Arranged vertically on the exterior of the building, to one side of the window 2, and suitably secured thereto in any desired or preferred manner, is a strip 3. On this strip there is hingedly supported, as at 4 the upper and lower arched members 5 of a frame. Connecting the upper and lower bars 5 are vertical bars 6, and centrally connecting the vertical bars is an arched bar 7. To the outer ends of the upper and lower 70 arched bars 5 of the frame there is hinged, as at 8 the back plate 9 of a box-like food receptacle or cabinet 10. The open front of the cabinet is closed by a hinged door 11, suitable latching means being provided between the door and cabinet. The interior of the cabinet may be suitably partitioned to provide the same with shelves or compartments.

75 The hinged connections 8 between the cabinet and the frame are disposed slightly beyond one of the sides of the window casing 2, and the device is arranged adjacent to the lower sash in the said casing.

When access is desired to the cabinet, the lower sash is raised, and the cabinet and frame are first swung outwardly to bring the door of the cabinet which is normally in contact with the outer wall of the building, away from the building. The cabinet is 90 thereafter swung upon its hinge connection 8 with the frame and the frame and cabinet are moved inwardly through the window opening. The door may be readily opened by the housewife and foodstuffs may be arranged in the cabinet or removed therefrom.

95 The device while primarily devised for preserving foodstuff in winter time may be also successfully used for ripening tomatoes or similar vegetables in the summertime, or as 100 a matter of fact may contain other foodstuffs in the summer time. The cabinet, when in its outer position will, as stated, rest against the outer wall of the building and by virtue of such contact will normally be held against 105 outward swinging, but to positively hold the cabinet against such swinging by wind storms, I provide latching means 12 between the said cabinet and the window casing. The construction is extremely simple, may 110 be cheaply manufactured, and readily attached to any ordinary construction of

buildings by an unskilled mechanic. The cabinet obviates the necessity of the employment of an ordinary refrigerator in the winter time and will be found exceptionally desirable in places where room space is required.

Having described the invention, I claim:

In a food cabinet, a vertically arranged plate designed to be secured to a support adjacent one edge of said support, a frame having upper and lower arched bars hingedly connected to the plate, vertical bars connect-

ing said upper and lower arched bars and a centrally arched bar connected to the vertical bars, a cabinet hingedly connected to the frame and susceptible to swinging thereon to bring the cabinet into contacting engagement with the support, means for locking the cabinet in such position, and said cabinet susceptible to swinging on and with the frame to arrange the same inwardly of but along one of the edges of the support.

In testimony whereof I affix my signature.

CHARLES TOTH PAPAY.
